(57) CLAIM

The ornamental design for an accessory for hand carts, as shown and described.

DESCRIPTION

FIG. 1 is a front perspective view of the accessory for hand carts;

FIG. 2 is a rear perspective view thereof;

FIG. 3 is a side view thereof, the opposite side being a mirror image thereof;

FIG. 4 is a front view thereof;

FIG. 5 is a rear view thereof;

FIG. 6 is a top view thereof; and,

FIG. 7 is a bottom view thereof.

The broken lines depict portions of the accessory for hand carts that form no part of the claimed design.
